(57) **CLAIM**

The ornamental design for a connector terminal, as shown and described.

DESCRIPTION

FIG. 1 is a front elevational view of a connector terminal showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view showing a front, top and right side thereof;

FIG. 8 is a perspective view showing a rear, bottom and left side thereof;

FIG. 9 is a perspective view showing a front, right and bottom side thereof; and,

FIG. 10 is a perspective view showing a rear, left and top side thereof.

The broken lines in the drawings illustrate portions of a connector terminal that form no part of the claimed design.

1 Claim, 7 Drawing Sheets
